UNITED STATES PATENT OFFICE.

CHARLIE C. PALMER, OF OSCEOLA, IOWA.

REGULATING MEANS FOR SELF-FEEDERS AND BAND-CUTTERS.

SPECIFICATION forming part of Letters Patent No. 732,956, dated July 7, 1903.

Application filed August 12, 1901. Serial No. 71,871. (No model.)

To all whom it may concern:

Be it known that I, CHARLIE C. PALMER, a citizen of the United States, residing at Osceola, in the county of Clark and State of Iowa, have invented new and useful Improvements in Regulating Means for Self-Feeders and Band-Cutters, of which the following is a specification.

This invention relates to improvements in self-feeders and band-cutters for threshing-machines, and refers more particularly to the means employed for regulating the supply of grain delivered to the threshing-cylinder.

The object of my invention is to provide a structure whereby the grain-bundles if too freely fed toward the cylinder of the thresher will automatically control the power-transmitting means, and thereby only permit the passage of a maximum amount of grain.

20 A further object of my invention is to provide a feed-regulating mechanism that in the event the grain be rapidly fed toward the cylinder to cause the delivery-belt to choke the continued pressure thereon will effect a reversal of said feeding-belt and cause the grain to be entirely removed from the entrance to the carrier leading to the cylinder, after which the belt will again gradually and automatically return to its normal movement.

25 In the meantime, however, the motion of the cylinder and its carrier will not be affected. Many other objects and advantages will be hereinafter referred to and be particularly pointed out in the claims.

30 In the drawings, Figure 1 is a side elevation of my improvement, showing its application. Fig. 2 is a perspective view of the grain-admission-regulating device. Fig. 3 is a top plan view. Fig. 4 is a detail section on line 4-4 of Fig. 1. Fig. 5 is a detail section on the line 5-5 of Fig. 1.

The same numerals refer to like parts in all the figures.

35 1 indicates the receiving end of a threshing-machine having the usual cylinder 2 of any well-known construction and being mounted on a shaft 3. A frame 4 projects from the thresher and is adapted to carry the mechanism for cutting and feeding the grain to the cylinder, together with the parts co-

operating therewith. Mounted in this frame are two shafts 5 and 6, provided with drums 8, around which an endless belt 9 passes and constitutes the "extension-carrier." The belt has the usual slats and fingers 10 to assist the bundles of grain to be fed toward the cylinder. In a plane below the extension-carrier is located the lower feed-carrier 11, composed in this instance of a series of parallel toothed bars 12, mounted at one end on a crank-shaft 13 and the opposite end being guided or supported in suitable ways. The inner end of the feed-carrier is in close proximity to the cylinder 2, so as to always supply a uniform and constant supply of grain thereto.

40 Mounted in the frame 4 on a crank-shaft 14 and rocking supports 15 are a series of forks 16, having a motion in a forwardly and downwardly direction and adapted to spread the bundles and assist in feeding the grain to the lower feed-carrier, it being understood any well-known means may be employed to cut the bundles of grain.

The mechanism thus far described relates 45 more particularly to what is substantially common in the art and only constitutes features with which my invention coacts.

40 Mounted in bearings 20 on the frame 4 is a shaft 21, carrying a sprocket-wheel 22 and 50 a friction-wheel 23, the latter being beveled out slightly to form a bearing-surface against which the friction-pinion 24 impinges. The pinion 24 is slidably mounted on a shaft 25 of such shape as will materially decrease the 55 thrust and reduce the friction of the working parts. The shaft for a portion of its length is in cross-section approximately a "Maltese cross," and the pinion 24 has an opening 26 of corresponding size and shape. To reduce 60 the friction to a minimum, the pinion 24 is provided with an antifriction-roller 25^a for each wing of the shaft 25, which makes the parts connected to said roll extremely sensitive in operation. On one end of the shaft 65 25 is fixed a worm 27, meshing with a worm-gear 28 on the shaft 6. Hence motion to the extension-belt is imparted from the friction-wheel 23.

55 On a rocking shaft 29, mounted above the 70

rear end of the extension-carrier, are a series of depending fingers 30, the lower end being of such distance from the belt as will permit the passage of a predetermined amount of grain before they are operated. A crank-arm 30^a extends from one end of the shaft 29 and is connected by a link 31 to an upright lever 32, pivoted to the frame at 33 and having its lower end forked and fitting a groove in the friction-pinion 24. Hence it will be seen that if the grain on the extension-carrier is of such height as will affect the movement of the fingers and rock the bar the friction-pinion will necessarily be moved lengthwise of its shaft.

A sprocket-chain 34, passing around the sprocket-wheel 35 on the crank-shaft 14, communicates a direct and constant rotary motion to the friction-gear 23 and to the shaft 13 through the medium of the sprocket-wheel 36.

From the foregoing description it is thought the operation of my invention will be readily understood by those skilled in the art to which it appertains. Motion is imparted to the shaft 14 from the wheel 39, imparting a kicking-forward movement of the forks, revolving the friction-gear 23, imparting a forward movement to the lower feed-carrier, revolving the friction-pinion-carrying shaft 25, 30 and the feed extension-belt. The bundles of grain are now delivered to the extension-belt and they are carried up and subjected to the action of the forks 16 to be equally spread over the lower feed-carrier. As before stated, the fingers 30 are of such height from the belt as will only permit a certain amount of grain to pass without imparting a rocking motion to the rock-shaft. Should, however, more grain be delivered to the carrier than can be acted on by the thresher-cylinder, it will force the fingers 30 in and rock the shaft 29, which movement will draw the friction-pinion 24 toward the center of the friction-gear 23, which by reason of the extension-carrier receiving its motion through this pinion the advance movement of the grain will be reduced and accordingly the amount of grain delivered to the lower feed-carrier. If the excess of grain continues to accumulate 45 in front of the fingers 30, the shaft 29 will continue to rock, whereupon the movement of the friction-pinion 24 is continued and will eventually pass to the opposite side of the center of the friction-gear, imparting a reverse motion to said friction-pinion, and necessarily to the extension feed-carrier. However, the movements of the forks, friction-gear, and the cylinder are uniformly the same. The reversing of the belt will naturally unload the grain, and when a sufficient quantity has been removed and the pressure of the grain against the fingers relieved the coacting levers will bring the friction-gear to its normal position and again the feed-belt 60 will feed the grain toward the cylinder. The weight of the fingers 30 and the coöperating

parts will readily return the pinion to its normal position, these elements being arranged and adjusted to bring about this result.

My improvement is especially well adapted for feeders and band-cutters where unskilled help is employed, and whenever an excessive supply of grain is delivered to the carrier by rash judgment the mechanism described will effectually prevent its choking the cylinder.

Having thus described my invention, what I claim is—

1. A machine for the purpose specified comprising a frame, a feed-carrier belt, a threshing-cylinder, a friction-gear, gearing which is constantly in contact with the friction-gear for communicating motion from said friction-gear to the feed-belt, and levers connected to said gearing for communicating motion from the gear to the friction feed-belt, in proximity to the belt for effecting the reversal of the motion of said belt, when it carries more than a predetermined supply of grain, substantially as described.

2. A machine for the purpose specified, comprising a frame, a feed-belt, a thresher-cylinder, a shaft, a beveled friction-pinion on the shaft adapted to move lengthwise thereon, a beveled friction-gear, a lever located in proximity to said feed-belt, and a second lever connected to the first-named lever for moving the friction-pinion toward and past the center of the friction-gear, to first stop and then reverse the movement of the feed-belt when the latter carries more than a predetermined supply of grain, substantially as described.

3. A machine for the purpose specified, comprising a frame, a thresher-cylinder, mechanism for feeding grain to said cylinder, a friction-gear revolving constantly at a given speed, a friction-pinion mounted on an angular shaft and adapted to always be in engagement with said friction-gear, mechanism for communicating motion from said angular shaft to the mechanism for feeding the grain, a trip and a series of levers connecting said trip and the friction-pinion for first retarding and secondly reversing the movement of the mechanism when more than a predetermined supply of grain on the belt moves the trip, its connecting-levers and the friction-pinion, to unload the excess of grain, the trip, its connection and the feeding means returning to their normal condition after the unloading of the excess of grain.

4. A machine for the purpose specified, comprising a frame, a thresher-cylinder, mechanism for feeding grain to said cylinder, a constantly-revolving friction-gear, a friction-pinion slidably mounted on a shaft and always in engagement with said friction-gear, a series of fingers depending from a rock-shaft constituting a trip, a pivoted lever forked at one end and engaging the friction-pinion, and a link connecting said pivoted lever and a crank on the end of the trip, for delivering a

predetermined amount of grain to the cylinder and adapted to reverse the movement of the feeding mechanism when the supply of grain exceeds the predetermined amount, to
5 unload the excess amount of grain, substantially as described.

In testimony whereof I have hereunto set

my hand in the presence of two subscribing witnesses.
